UNITED STATES PATENT OFFICE.

MARI SCHÜTZ, OF NEW YORK, N. Y.

DESIGN FOR A HAIR-CRIMPER.

SPECIFICATION forming part of Design No. 23,016, dated January 23, 1894.

Application filed December 23, 1893. Serial No. 494,604. Term of patent 7 years.

To all whom it may concern:

Be it known that I, MARI SCHÜTZ, a citizen of the United States, residing in the city, county, and State of New York, have invented 5 and produced a new and original Design for a Hair Crimper or Waver, of which the following is a specification, reference being had to the accompanying drawings, in which—

Figure 1 is an elevation showing my de- 10 sign, and Fig. 2 is an edge view.

The leading feature of my design consists in the parallel edges joined by half circle curves.

The outer edges of the parts *a* and *b* are 15 straight and parallel, and the outer edges of the part *c* are parallel half circles. The end

of the part *b* is approximately a half circle perforated at *d*. The inner edges of the part *a* are parallel and joined by a half circle at *e* and the edges at the outer end of the part *a* 20 diverge and are rounded, as shown at *i*.

As viewed in Fig. 2, the sides are parallel to one another and quite close together.

What I claim is—

The design for the hair crimper or waver, 25 substantially as shown and set forth.

Signed by me this 21st day of December, A. D. 1893.

MARI SCHÜTZ.
